UNITED STATES PATENT OFFICE

2,229,188

LOOM

Sarah P. C. Porter, Salt Lake City, Utah

Application August 14, 1939, Serial No. 289,944

3 Claims. (Cl. 139—34)

My invention relates to weaving looms and has for its object to provide a new and highly efficient loom which will be adjustable as to size, and which has new features incorporated therein which enable the user to more quickly string the loom and provide quicker weaving thereon.

A further object is to provide a loom which has the fingers of the comb bent back so that the base threads will not slip therefrom and on which I use an improved needle and shuttle, with a new method of securing the weaving fabrics together into a single strand.

A still further object is to provide a comb for looms which being formed in my particular design provides a loom which when used in hand rug weaving eliminates the extra web around the perimeter.

A still further object is to provide a new method of attaching strands of fabric into one continuous strand without the bulging knots now commonly used.

A still further object is to provide a newly formed finger for weaving combs which if desired may be made in single fingers and attached to a common base.

These and other objects I accomplish with the device illustrated in the accompanying drawings in which similar numerals and letters of reference indicate like parts throughout the several views and as described in the specification forming a part of this application and pointed out in the appended claims.

In the drawings in which I have shown the various modifications and details of my loom and its cooperative parts.

Figure 1 is a plan view of the loom parts cut away to show that the length is variable.

Figure 2 is a side elevation of Figure 1.

Figure 3 is a section on line 3—3 of Figure 1.

Figure 4 is a plan view of a section of the loom showing means for extending the length of the sides.

Figure 5 is a side view of Figure 4.

Figure 6 is a plan view of a simplified type of the device made preferably stamped from metal without any reinforcing of wood.

Figure 7 is an edge elevation of Figure 6.

Figure 8 is a plan view of a weaving stick used with the loom.

Figure 9 is an edge view of Figure 8.

Figure 10 is a plan view of a modified weaving stick and string fastener.

Figure 11 is a plan view of a shuttle for use with my loom.

Figure 12 is an enlarged view of the shuttle

with the weaving stick formed as a part thereof.

Figure 13 is a corner brace for the loom to be used when necessary.

Figure 14 is a T-connection for some types of looms.

Figure 15 is a channel connection to reinforce the sides and joints in the sides of the loom.

Figure 16 is a view showing the use of the weaving stick and string or fabric-joining-method employed to make the string into lengths.

Figure 17 is a modified type of loom shown in perspective.

In the drawings, I have shown the loom as A, made of two like sides 5 and 6, and two like ends 7 and 8, each of which side pieces is secured to the ends by thumb screws and bolts 9 and 10. The side pieces are made of a strip of metal 11 formed with the inner edges formed of spaced apart fingers 12 bent vertical at 13 in relation to the metal 11 and then bent back 20 parallel at 14 to form U-shaped hooks on each finger. The strip of metal is then set in a rabbed wooden strip 15.

The end pieces are made of a flat strip of metal 11a identical in form to that of the side pieces but having only a reinforcing strip of wood 16 secured along one side. Spaced apart holes a and b are bored through the ends and sides respectively to provide for various adjustments of the ends and sides to make other forms than the square loom as shown in Figure 1.

In Figures 4 and 5, I have shown a tongue and groove adjustment for ends of abutting side or end pieces to permit for additional length when needed and these joints are made of a 35 female grooved strip 18 and a male tongue 19 fitted therein and held in place by a thumb screw 20.

Figures 6 and 7 show the metal strips 11 and 11a removed from the wood and provided with 40 more closely spaced holes in the event that two thumb screws 21 and 22 are desired or are required.

Figures 8 and 9 show a weaving stick B to be used in weaving upon the loom and the stick 45 is made of a strip 23 having a hole 24 near the pointed end 25 and with two holes 26 and 27 in the body of the strip or weaving stick. The string or fabric which is being used for weaving is shown threaded through the lower hole 27, then 50 through the end hole 24, and back through the hole 26, with the end of the string through the hole and held in place by the loop of the fabric passing through the other two holes. The stick is then woven through the web of the loom.

In Figures 10, 11 and 12, I have shown different modifications of weaving sticks, shuttle combinations, and string or fabric knotting or fastening means, and

5 In Figure 10 I have shown the weaving stick and string fastener as made of a long rod or body 30 having an elongated slot 31 therein, said slot having one edge cut away at 32 to provide an easy threading slot. The end 33 of the body 10 is sharpened to permit it being thrust through a strip of fabric from which the string for weaving is made or for threading between the threads of the web of the loom.

Figure 11 shows a short bodied stick 30a having each end pointed at 33a and with spaced apart opposed slots 31a and 31b formed therein. This type of stick or shuttle may be used for weaving, tying strings, or otherwise as desired.

In Figure 12 the only modification which I 20 have made from that shown in Figure 11 is making the entire body larger and longer and providing additional spaced apart pairs of holes 34 at each end thereof to make a device which may be used as that one shown as a weaving stick, 25 shown in Figures 8 and 9. Thus, the entire combination of weaving stick, shuttle, string fastener, and shuttle may be made in one combination.

Figure 13 shows a right angled brace 37 perforated at 38 for securing bolts and this brace 30 may be utilized to brace the corners of the loom shown in Figures 1 or 6.

Figure 14 shows a T-shaped brace member 39, perforated at 40, said brace to be used on a loom having a dividing partition.

35 Figure 15 shows a channel brace 41 perforated at 42 to be used to brace continuation or straight joints in the sides of extra long looms.

Figure 16 shows the method employed for tying the knot C shown in the weaving string or 40 material D, for adding strength and also for fastening the additional lengths. This is done by passing the sharpened end 33 through the end of the fabric to be tied on the string, then passing the end 33 through the end of the fabric 45 already on the string. Then by looping the end of the new piece of fabric through the slot 31, then the entire form of fabric is withdrawn from the stick which results in the knot shown as C.

In Figure 17 I have shown a modified type of 50 loom which consists of flat plates or strips of metal 35 to be secured together at the ends by an angled brace 36 and held in place by spaced apart bolts or rivets and the edges of the two

strips 35 are formed into extended fingers 37 for placing the web on, and these fingers as shown, are bent back upon themselves making it impossible for the web to come off from the fingers. However, if that causes too much loss of time 5 when taking down the finished product, the fingers may be bent only once, as shown at 38, making a single finger bend. It will be obvious that double or single fingers may be used and attached to a long board or metal frame so that 10 a purchaser may buy as many fingers as they wish and attach them to any frame or loom base, and such modifications and changes are considered a part of this invention and within the scope 15 of the claims.

Having thus described my invention, I desire to secure by Letters Patent and claim:

1. A weaving loom comprising opposed like sides secured spaced apart by opposed like ends with the sides and ends carrying metal strips 20 secured thereto, said strips having their inner edges formed as extended fingers bent upwardly and back parallel forming U-shaped thread retaining members and with the sides having similar metal strips, the strips being inserted in 25 slotted recesses in the sides and secured onto the under surfaces of the ends to place the fingers in substantial alignment.

2. A weaving loom comprising metal strips of like form each being provided with fingers formed 30 along the inner edges, each finger being bent back parallel with the body of the strip; a body for each strip made of wood with the end bodies made with recesses therein in which the metal strips are secured and with the sides secured 35 onto the underside of their complementary wooden bodies; and means to secure the four corners together forming a four sided loom.

3. A loom comprising four flat elongated strips of metal having one edge of each formed with 40 extended fingers bent upwardly and back parallel with the metal strips; wooden frame pieces secured onto the top side of two of such strips to form the ends of the loom; wooden frame pieces having a recess cut therein with the top 45 side of the recess shorter than the base side and with the two strips for the sides secured in said slits to place the four metal strips in close alignment with each other; spaced holes in the wooden frame pieces; and securing screws passed 50 through said holes to hold the four members in rectangular relationship.

SARAH P. C. PORTER.
